US00D968168S

(12) **United States Design Patent** (10) **Patent No.:** **US D968,168 S**
(45) **Date of Patent:** **** Nov. 1, 2022**

(54) **CUP**

(71) Applicant: **ZHEJIANG PROVINCE YONGKANG CITY KANGFUTE INDUSTRIAL CO., LTD.**, Jinhua (CN)

(72) Inventor: **Peixiu Hu**, Jinhua (CN)

(73) Assignee: **ZHEJIANG PROVINCE YONGKANG CITY KANGFUTE INDUSTRIAL CO., LTD.**, Jinhua (CN)

(**) Term: **15 Years**

(21) Appl. No.: **29/759,904**

(22) Filed: **Nov. 25, 2020**

(30) **Foreign Application Priority Data**

May 25, 2020 (CN) 202030245461.1

(51) **LOC (13) Cl.** **07-01**

(52) **U.S. Cl.**

USPC **D7/536; D7/511**

(58) **Field of Classification Search**
